UNITED STATES PATENT OFFICE.

PETER ENOCH SHIRK, OF BLUE BALL, ASSIGNOR OF THREE-FOURTHS TO
WILLIAM H. LAWSON, OF HONEY BROOK, PENNSYLVANIA.

THILL-COUPING.

SPECIFICATION forming part of Letters Patent No. 374,634, dated December 13, 1887.

Application filed May 28, 1887. Serial No. 239,688. (No model.)

To all whom it may concern:

Be it known that I, PETER ENOCH SHIRK, of Blue Ball, in the county of Lancaster and State of Pennsylvania, have invented certain 5 Improvements in Thill-Couplings, of which the following is a specification.

The aim of my invention is to provide an adjustable device applicable to thill-couplings such as are now in general use without change 10 or alteration therein to prevent the rattling of the thills.

Referring to the accompanying drawings, Figure 1 represents a side elevation of a clip having my device applied thereto. Fig. 2 is 15 a top plan view of the same. Fig. 3 is a section on the line $x-x$ of Fig. 2. Fig. 4 is a perspective view showing the parts of my attachment separated from each other and from the coupling.

20 Referring to the drawings, A represents the thill-iron mounted at its rear end on the transverse bolt B, which is seated at its ends in the forwardly-projecting arms a of the clip C, which latter is mounted on the axle D and 25 secured at its lower end by the clip-plate E and nuts b.

The foregoing parts are of ordinary construction, and are of the form at present in almost universal use. My device is designed 30 particularly for application to this form of thill-coupling.

The device consists, first, of a rubber block, c, recessed in its forward face and adapted to fit against and around the thill-iron between 35 the arms of the supporting-clip, and, second, of a metallic plate, d, adapted to fit against the rear side of the rubber block, with an arm to engage over its top, and also with a depending arm or stem, d', which is carried 40 downward and forward through a plate or washer, e, and connected at the lower end by a horizontal pivot, f, to a cam-lever, g, the lower end of which is preferably provided with a strap-opening, as shown.

45 In making use of the device the bolt is removed and the thill removed from its clip, the device inserted between the arms of the clip, and the thill inserted and secured by the bolt, as shown in Figs. 2 and 3. When the 50 parts are thus assembled, the rear end of the

clip resting in the concave face of the rubber holds the same in position, and the rubber in turn holds the plate d. The cam-lever is next turned forward from its original position (shown by dotted lines in Fig. 3) to the position shown by full lines in the same figure, the effect of which is to force the washer e upward and turn the plate d downward, thereby subjecting the rubber to a vertical compression and crowding it tightly around and 55 against the end of the thill, the effect being, as the rubber and plate are supported by the bearing of the latter against the face of the clip C, to hold the thill iron snugly to its place and render its action entirely noiseless. A 60 strap, G, passed from the thill through the end of the cam-lever, will serve the double purpose of preventing the lever from being accidentally thrown out of position and of retaining the thill in the event of the bolt or 65 other part giving away.

I am aware that various devices have been contrived for securing and confining rubber and other elastic material against a thill-iron, and this I do not broadly claim; but I believe 75 myself to be the first to provide a cushion and compressing device such as herein described, adapted for application to thill clips or couplings of ordinary form.

My device is highly advantageous in that it 80 may be quickly applied to or removed from existing couplings without the employment of special tools or instruments for the purpose, and that when the rubber is released from compression the latter ceases its pressure upon 85 the thill-iron, allowing the bolts to be readily withdrawn without mutilating or injuring its thread.

Having thus described my invention, what I claim is—

1. The anti-rattling attachment for a thill-coupling, consisting of the recessed elastic block, the plate adapted to engage over and behind the same, and provided with an extended end, the washer encircling said end 90 and bearing against the cushion, and the eccentric lever applied to said end outside of the washer.

2. In combination with a thill iron and clip of ordinary form, as represented, the anti-rat- 100

tling attachment consisting of the recessed rubber block seated over and around the thill-
iron, the metal plate bearing between the face of the clip and the rear face of the block and
5 engaging over the latter, the underlying washer, and the eccentric lever.

In testimony whereof I hereunto set my hand,

this 18th day of May, 1887, in the presence of two attesting witnesses.

PETER ENOCH SHIRK.
